EXTENSIBLE DRAWER MOUNTING

Ulysses G. McQueen, Beverly Hills, Calif.

Application June 18, 1934, Serial No. 731,136

12 Claims. (Cl. 45—77)

This invention relates generally to drawers for desks, cabinets and other articles of furniture, and more particularly to means for extensibly mounting such drawers.

- 5 One object of the invention is to provide a mounting structurally characterized by a minimum number of inexpensively constructed parts which are functionally related in a manner to co-act in mounting a drawer for movement while 10 enabling the drawer to be withdrawn to a fully opened position in which the drawer will be rigidly supported and yet can be actuated with ease, all without the use of expensive anti-friction and complex guiding devices.
- 15 Another object of the invention is to provide a drawer mounting the parts of which can be readily stamped from sheet metal and can be assembled and correlated with an article of furniture and with a drawer thereon with ease and 20 dispatch to function as an extremely durable and positively acting extensible support for the drawer.

With these and other objects in view, the invention consists in the novel construction and arrangement of parts as set forth in the following specification and particularly pointed out in the appended claims.

In the accompanying drawings,

Figure 1 is a view showing, in side elevation, the extensible drawer mounting associated with an article of furniture and with a drawer occupying its closed position;

Figure 2 is a view similar to Figure 1, but showing the drawer in its fully opened position;

Figure 3 is a transverse sectional view taken on the line 3—3 of Figure 1;

Figure 4 is a horizontal sectional view taken on the line 4—4 of Figure 1;

Figure 5 is a view similar to Figure 4, but taken on the line 5—5 of Figure 2;

Figure 6 is an enlarged fragmentary transverse sectional view taken on the line 6—6 of Figure 1;

Figure 7 is a perspective view of a fixed or stationary supported member embodied in the invention;

Figure 8 is a perspective view of a slide member embodied in the invention;

Figure 9 is a perspective view of a bracket or shoe embodied in the invention.

In its application to an article of furniture for the extensible mounting of a drawer therein, the invention comprises two units U and U' which are identical in construction with the exception

of being right and left hand, respectively, as they are associated with opposite sides of a drawer.

A detailed description of one of the two units illustrated in Figure 3 will, therefore, suffice. Each unit comprises a stationary supporting member M in the form of a sheet metal plate of generally rectangular outline, the body portion 10 of which is provided with openings 11—11 through which fastening members, such as headed screws 12, are passed and are screwed into a vertical wall 13 of a drawer receiving opening 14 in an article of furniture so that the length of the plate will be disposed horizontally and adjacent the front of the opening 14. From one longitudinal edge of the body portion 10 which in the applied position of the member is its bottom edge, projects laterally inward, a base flange 15.

From the other longitudinal or top edge of the body portion 10 projects laterally and horizontally inward a flange 16 terminating in a vertically disposed rail 17 which projects upwardly from the inner or free edge of the flange, all as clearly shown in Figure 6. Adjacent the rear end of the body portion 10, a lug 18 is struck laterally so as to be vertically disposed, and is covered by a sleeve or band of elastic rubber 19 to provide a cushioned stop 20.

A slide member S is associated with the supporting member M and is in the form of a sheet metal plate of generally rectangular outline of a height approximating that of the member M and of a length somewhat in excess of two lengths of the member M. One longitudinal edge of the body portion 21 of the member S which constitutes its top edge in the operating position of the member, is provided with a return bend forming a portion of U-shaped cross section which provides a runner 22 receiving the rail 17 so as to ride or slide on the latter. Instruck laterally from the body portion 21 of the slide member so as to extend longitudinally of the member adjacent its top edge is a retaining flange 23 which underlies the flange 16 of the supporting member so as to co-act with the latter and with the runner 22 in confining the slide member against displacement vertically from the supporting member.

The lower part of the body portion 21 is laterally bent angularly throughout its length as indicated at 24 and then in parallelism at 25 which latter portion is adapted to ride against the inner face of the body portion 10 of the supporting member M and upon the base flange 15 of the latter. Adjacent its rear end the body portion 21 of the slide member is outstruck laterally to form a 55

lug 26 vertically disposed and covered by a sleeve or band 27 of elastic rubber to provide a cushioned stop 28 which co-acts with the stop 29 of the supporting member M in definitely limiting the forward movement of the slide member S at the projected position relative to the drawer receiving opening 13, as shown in Figures 2 and 5.

In conjunction with the supporting and slide members M and S, respectively, brackets B and B' are provided, these brackets being identical in construction and each being in the form of a metallic plate which is secured by screws 29 to a vertical side wall 30 of a drawer D, one of the brackets being disposed at the rear end of the drawer and the other being spaced a considerable distance forwardly therefrom. Each bracket is laterally and then downwardly bent to provide a horizontal flange 31 and a vertically depending flange 32 which co-act with the confronting vertical face of the drawer wall 30 in providing an upwardly opening guideway which receives the runner 22 so as to mount the drawer on the slide member S for sliding movement relative thereto from the closed position of the drawer shown in Figures 1 and 3 to the fully opened position of the drawer shown in Figures 2 and 5, and wherein the slide member S is fully projected and the forward bracket B co-acts with a laterally projecting lug 33 on the forward end of the runner 22 of the slide member.

The operation of the invention is as follows:

Prior to the installation of the two units U and U', the lug 33 of the slide member S of each unit occupies a position in alignment with the vertical flange of the runner 22, of which flange the lug originally forms the forward end, as shown in Figure 8. Following the mounting of the drawer D on the slide members of the units by means of the brackets B and B' of the respective units, and with the slide member of each unit projecting from the drawer receiving opening 14 the lug 33 is accessible for bending to the right angular and active position shown in Figures 1, 2, 4 and 5.

In now actuating the drawer to move same from the closed position shown in Figures 1 and 4 to the fully opened position shown in Figures 2 and 5, the forward brackets B of the respective units U and U' will engage the lugs 33 of the respective slide members S to advance the latter from the retracted position shown in Figures 1 and 4 to the projected position shown in Figures 2 and 5. It will be clear that the runners 22 of the slide members will ride upon the rails 17 of the respective supporting members M so as to accurately guide the slide members in rectilinear paths and that the slide members are confined against tilting in a vertical plane by the co-action of the runners 22 and the retaining flanges 23 with the rails 17 and the flanges 16, respectively, of the supporting members.

The lugs 33 co-act with the brackets B to definitely determine the extended position of the drawer relative to the slide members, or to express this functioning in another manner, the lugs and brackets co-act to definitely limit the opening movement of the drawer relative to the slide members.

The stops 28 and 29 of the supporting and slide members, respectively, co-act in definitely determining the projected position of the slide members relative to the supporting members, or in other words definitely limit the advancing movement of the slide members relative to the supporting members, all with the result that the drawer in its fully open position will be rigidly

supported from the slide members by the pairs of brackets B and B' which function as hangers.

Should there be any tendency of the drawer to tilt downwardly at its forward end about the forward brackets B as fulcrums due to overloading of the forward portion of the drawer, the rear end of the drawer which in the extended position of the drawer is disposed within the opening 14, engages the top wall of the opening at the front of the article of furniture so as to positively prevent such tilting movement.

It will be apparent that during the closing movement of the drawer, the slide members will be caused to retract relative to the drawer by the laterally overhanging side edges of the drawer front so as to finally occupy the fully retracted position shown in Figures 1 and 4, when the drawer is closed.

What is claimed is:

1. In a drawer mounting, a member adapted to be fixed to a support and having a rail; a slide member having a runner mounted on said rail for movement of the slide member to retracted and projected positions relative to the fixed member; co-acting means on said members for limiting the projecting movement of the slide member; spaced brackets adapted to be secured to a side wall of a drawer and having portions co-acting with said runner to mount the drawer on the slide member for forward and rearward movements relatively thereto; and means on the slide member co-acting with one of said brackets to limit the forward movement of the drawer relative to the slide member.

2. In a drawer mounting, a member adapted to be fixed to a support and having a rail; a slide member having a runner mounted on said rail for movement of the slide member to retracted and projected positions relative to the fixed member; co-acting means on said members for limiting the projecting movement of the slide member; means defining hangers adapted to be secured in spaced relationship to the side of a drawer and being slidably mounted on said runner to suspend the drawer from the slide member for forward and rearward movements relatively thereto; and a lug on the runner disposed for engagement by one of said hangers to limit the forward movement of the drawer relative to the slide member.

3. In a drawer mounting, a member adapted to be fixed to a support and having a vertical rail; a slide member having an inverted U-shaped flange defining a runner receiving said rail to mount the slide member for movement to retracted and projected positions relative to the fixed member; co-acting means on said members for limiting the projecting movement of the slide member; means for slidably mounting a drawer on the slide member for forward and rearward movements relatively thereto; and means for limiting the forward movement of the drawer relative to the slide member.

4. In a drawer mounting, a member adapted to be fixed to a support and having a vertical rail; a slide member having an inverted U-shaped flange defining a runner receiving said rail to mount the slide member for movement to retracted and projected positions relative to the fixed member; co-acting means on said members for limiting the projecting movement of the slide member; means defining hangers adapted to be secured to a side wall of a drawer at spaced locations along the length of the latter and being mounted on said runner to slidably

- mount the drawer for forward and rearward movements relative to the slide member; and means for limiting the forward movement of the drawer relative to the slide members.
5. In a drawer mounting, a member adapted to be fixed to a support and having a vertical rail; a slide member having an inverted U-shaped flange defining a runner receiving said rail to mount the slide member for movement to retracted and projected positions relative to the fixed member; co-acting means on said members for limiting the projecting movement of the slide member; means defining hangers adapted to be secured to a side wall of a drawer at spaced locations along the length of the latter and being mounted on said runner to slidably mount the drawer for forward and rearward movements relative to the slide member; and a lug on the runner disposed to be engaged by one of the said hangers to limit the forward movement of the drawer relative to the slide member.
6. In a drawer mounting, a member adapted to be fixed to a support and having a vertical rail; a slide member having an inverted U-shaped flange defining a runner receiving said rail to mount the slide member for movement to retracted and projected positions relative to the fixed member; a flange on the slide member co-acting with the runner of the latter and with the rail of the fixed member to confine the slide member against angular displacement relative to the fixed member; co-acting means on the members for limiting the projecting movement of the slide member; means adapted to be secured to a drawer and co-acting with said runner to slidably mount the drawer on the slide member for forward and rearward movements relatively thereto; and means on the slide member co-acting with the last means to limit the forward movement of the drawer relative to the slide member.
7. In a drawer mounting, a member adapted to be fixed to a support and having a lateral flange terminating in an upwardly projecting rail; a slide member having an inverted U-shaped portion defining a runner receiving said rail to slidably mount the slide member on the fixed member for movement to retracted and projected positions; a lateral flange on the slide member underlying said lateral flange of the fixed member for co-action therewith and with said rail and runner to confine the slide member against lateral displacement relative to the fixed member; co-acting means on said members for limiting the projected movement of the slide member; means for slidably mounting a drawer on the slide member for forward and rearward movements relatively thereto; and means for limiting the forward movement of the drawer relative to the slide member.
8. In a drawer mounting, a member adapted to be fixed to a support and having a lateral flange terminating in an upwardly projecting rail; a slide member having an inverted U-shaped portion defining a runner receiving said rail to slidably mount the slide member on the fixed member for movement to retracted and projected positions; a lateral flange on the slide member underlying said lateral flange of the fixed member for coaction therewith and with said rail and runner to confine the slide member against lateral displacement relative to the fixed member; co-acting means on said members for limiting the projecting movement of the slide member; means defining hangers adapted to be se-

cured to a side wall of a drawer at spaced locations along the length of the drawer and being mounted on said runner to slidably mount the drawer for forward and rearward movements relative to the slide member; and a stop on the slide member disposed to be engaged by one of said hangers to limit the forward movement of the drawer relative to the slide member.

9. In a drawer mounting, a member adapted to be fixed to a support and having a vertical rail; a slide member having an inverted U-shaped flange defining a runner receiving said rail to mount the slide member for movement to retracted and projected positions relative to the fixed member; brackets adapted to be secured to a side wall of a drawer at spaced locations along the length of the drawer and having angularly related flanges disposed to co-act with said side wall of the drawer in providing guideways in which said runner is received to slidably mount the drawer on the slide member for forward and rearward movements relatively thereto; and means for limiting the forward movement of the drawer relative to the slide member.

10. In a drawer mounting, a member adapted to be fixed to a support and having a vertical rail; a slide member having an inverted U-shaped flange defining a runner receiving said rail to mount the slide member for movement to retracted and projected positions relative to the fixed member; brackets adapted to be secured to a side wall of a drawer at spaced locations along the length of the drawer and having angularly related flanges disposed to co-act with said side wall of the drawer in providing guideways in which said runner is received to slidably mount the drawer on the slide member for forward and rearward movements relatively thereto; and a lug on the forward end of the runner disposed to be engaged by one of said brackets to advance the slide member to projected position and to limit the forward movement of the drawer relative to the slide member.

11. In a drawer mounting, a fixed member comprising a plate adapted to be secured in a vertical position to a support and having a lateral base flange and a lateral top flange terminating in a vertical rail projecting upwardly from said lateral top flange; a slide member comprising a plate having a runner of inverted U-shaped cross section along its upper edge receiving said rail to mount the slide member on the fixed member for movement to retracted and projected positions relatively thereto; a lateral flange projecting from the slide member to underlie said lateral top flange for co-action therewith and with the rail and runner in confining the slide member against lateral displacement on the fixed member; the lower portion of the slide member being laterally offset to ride against the inner side of the fixed member and upon the base flange of the latter; co-acting means on said members for limiting the projecting movement of the slide member relative to the fixed member; means for mounting a drawer on the slide member for forward and rearward movements relatively thereto; and means for limiting the forward movement of the drawer relative to the slide member.

12. In a drawer mounting, a fixed member comprising a plate adapted to be secured in a vertical position to a support and having a lateral base flange and a lateral top flange terminating in a vertical rail projecting upwardly from said lateral top flange; a slide member compris-

ing a plate having a runner of inverted U-shaped cross section along its upper edge receiving said rail to mount the slide member on the fixed member for movement to retracted and projected positions relatively thereto; a lateral flange projecting from the slide member to underlie said lateral top flange for co-action therewith and with the rail and runner in confining the slide member against lateral displacement on the fixed member; the lower portion of the slide member being laterally offset to ride against the inner side of the fixed member and upon the base flange of the latter; co-acting means on said members

for limiting the projecting movement of the slide member relative to the fixed member; brackets adapted to be secured to a side wall of a drawer at spaced locations along the length of the latter and having portions defining guideways receiving said runner to mount the drawer on the slide member for forward and rearward movements relatively thereto; and a lug on the forward end of the runner disposed to be engaged by one of said brackets to advance the slide member to projected position and to limit the forward movement of the drawer relative to the slide member. 5 10
